BOTTLE RINSING MACHINE

Filed March 19, 1928

INVENTOR.

Frederick Boeschel

BY

Wm. Boddy ATTORNEY.

UNITED STATES PATENT OFFICE

FREDERICK BOESCHEL, OF EAST RUTHERFORD, NEW JERSEY

BOTTLE-RINSING MACHINE

Application filed March 19, 1928. Serial No. 262,820.

The present invention relates to bottle rinsing machines of the class designed more particularly for cleansing relatively small perfume bottles.

5 The objects of the present invention include means for conserving the cleaning fluid by repeatedly circulating and purifying the same.

A further object is to provide detachable 10 filtering devices that may be readily removed and their several parts cleaned and replaced.

Also to provide a detachable nozzle head having a pair of spray nozzles over which the operator may use both hands and position 15 two bottles at a time and jointly effect the necessary pressure for circulating and spraying the cleaning fluid.

For further comprehension of the invention, and of the objects and advantages thereto 20 of, reference is had to the following description and accompanying drawings, and to the appended claims in which the various features of the invention are more particularly pointed out.

25 Referring to the drawing in which similar characters of reference designate like parts throughout the several views:

Figure 1 of the drawings illustrates my invention in sectional elevation and Figure 2 30 is an enlarged detail view of a filtering device shown in connection with a pump plunger.

Numeral 5 of the drawing indicates a fluid reservoir or tank having a bottom wall 6 and 35 upwardly and inwardly flaring side walls 7 comprising the lower or body portion of the tank, and at the upper end thereof a hopper section 8 is formed provided with upwardly and outwardly flaring side walls 9.

Mounted within the tank is a pump-casing 40 10, provided with a bottom flange 11 fixed to the bottom wall 6 of the tank. Inlet ports 12 extend through the wall of the casing adjacent the lower end thereof, and above the ports an inwardly extending valve seat 13 is 45 formed within the casing, the valve seat being provided with a ball check-valve 14, and disposed above the valve is a stop composed of cross wires 15 fixed in the walls of the casing.

50 At the upper end of the pump-casing 10, a

cap or closure 16 is detachably secured thereto by screw-threads, and fixed to and extending above the cap are a pair of grip-pins 17 by means of which the cap may be readily detached or secured in position. The cap is provided with a central perforation through which is slidably mounted a tubular pump-rod 18 having at its lower end an exteriorly threaded portion adapted to detachably secure a piston comprising a pair of threaded washers 19 having an interposed relatively soft packing or piston member 20 closely engaging the inner walls of the pump casing. Fixed to the piston-rod 18 above the piston is a sleeve 21 that serves by its engagement with the cap 16 as a stop to limit the upward movement of the piston.

A nozzle-head 22 is detachably secured to the upper end of the tubular piston-rod 18, and detachably secured to the nozzle-head are a pair of spray nozzles 23 having central passages leading through cross passages 24 in the head from the central passage 25 of the pump-rod 18. Lateral spray passages are formed in the outer ends of the nozzles 23, and grooves 26 are formed in the seats of the nozzle head surrounding the nozzles to provide escape for the cleaning fluid discharged from the mouths of the bottles, the latter being indicated by dotted lines 27. In its discharge from the bottles the cleaning fluid flows by gravity into the receiving hopper 8.

A main filtering device is provided for the bottom of hopper consisting of a perforated strainer plate 28 fixed to the top of the cap 16 of the pump-casing, and upon the strainer plate a circular filter fabric 29 is laid, the marginal edges 30 thereof overlapping the angular side walls 9 of the hopper. A washer 31 is also provided for the filter and centrally overlays the fabric, the several parts including the strainer plate being provided with perforations to receive the tubular pump-rod 18 and the grip-pins 17, and by means of the latter the cap 16 may be readily unscrewed from the pump-casing 10, and the filtering device, pump-rod and piston quickly removed for cleaning and repairs. Surrounding the pump-rod 18 is a helical com-

pression spring 32, the opposite upper and lower ends thereof thrusting respectively against the nozzle-head 22 and the washer 31, thus normally acting to hold the parts 5 of the filtering device together against the cap 16 and to yieldingly urge the pump-piston into its upper position shown in Fig. 1.

In its upward movement the pump-piston 20 raises the check-valve 14 off its seat and 10 draws the liquid from the tank 5 through the ports 12 into the casing 10. For providing against solid impurities entering and choking up the spray nozzles due to accidental displacement of the main filtering device, 15 the inlet ports 12 of the pump-casing are surrounded in spaced relation with an auxiliary suction filter 33 having perforated side walls exteriorly protected by a suitable filter fabric 34.

20 In the operation of the rinsing machine the attendant may use both hands and place a pair of bottles over the nozzles 23 and by exerting downward pressure through the bottles against the nozzle-head 22 will de- 25 press the pump-rod 18 and piston 20 against the yielding resistance of the spring 32, the downward movement of the piston closing the check-valve 14 and forcing the liquid upwardly through the downwardly moving 30 tubular pump-rod 18 and out through the spray nozzles 23 to the interior of the bottles, and then out through the mouths of the latter into the receiving hopper 8, the liquid portions passing through the cup- 35 shaped filtering fabric 29 while the solid impurities are retained by the filter.

The angular marginal portion 30 of the filter fabric overlapping the side walls of the hopper provides a close joint that permits 40 only the liquid portions of the rinsing solution to pass into the tank 5 for recirculation and use. By thus separating the solid impurities considerable saving may be effected in the quantity of cleansing liquid consumed 45 and which commonly consists wholly or in part of alcohol or similar volatile agents.

I claim:

1. In a bottle rinsing device, a fluid receiving tank having at its upper end a hopper 50 provided with outwardly flaring side walls, a pump casing fixed within said tank and having at its lower end a valve controlled inlet, a cap detachably secured at the upper end of said casing, a tubular pump rod slidable in 55 said cap and having at its lower end a piston slidable in said pump casing, a nozzle-head at the upper end of said tubular rod, and a filtering device detachably secured to said cap and removable therewith, the said 60 filtering device having marginal edges engag- 65 gaging the flaring walls of said hopper.

2. In a bottle rinsing device including a tank provided with a receiving hopper, a circu- 65 lating pump having a casing provided at its upper end with a detachable cap, and

a filtering device secured to said cap and removable therewith having outwardly flaring marginal edges engaging the walls of said receiving hopper.

Signed at New York in the county of New York and State of New York this 21st day of February, A. D. 1928.

FREDERICK BOESCHEL.
